BOX PRESS

**Lloyd E. Jones and Henry L. Smith, Dunedin,
Fla., assignors to Food Machinery Corporation,
San Jose, Calif., a corporation of Delaware**

Application March 12, 1937, Serial No. 130,556

10 Claims. (Cl. 100—57)

This invention relates to a box handling apparatus and more particularly to an improved box press or the like for clamping lids on boxes of fruit and the like to enable fastening of the lid.

It is an object of the invention to provide an improved box press or the like which can readily be adjusted for use with various sizes of boxes.

Another object of the invention is to provide an improved box press having adjustable presser arms to adapt the box press for use with various sizes of boxes.

Another object of the invention is to provide an improved box press having adjustable presser arms to adapt the box press for use with various sizes of boxes and which can be applied as an attachment to box presses already in use.

Another object of the invention is to provide an improved box press or the like which is of a sturdy, simple construction which is not likely to get out of order and which is designed to promote economical manufacture and assembly.

Other objects will appear as the description progresses.

25 In the drawings:

Fig. 1 is a front elevation of a box press embodying my invention with a box shown in place, and with the raised inoperative position of the presser arms shown in dotted lines.

30 Fig. 2 is a side elevation of the box press shown in Fig. 1 and also illustrates the inoperative position of the presser arms in dotted lines.

Figs. 3 and 4 are enlarged front and side elevations respectively of the right end presser arm assembly as viewed in Fig. 1.

Fig. 5 is a diagrammatic view illustrating the various adjusted positions of the presser arm illustrated in Figs. 3 and 4.

Fig. 6 is a detail section illustrating the locking pin structure, the view being indicated by the line 6—6 in Fig. 3.

Fig. 7 is a perspective view of the locking pin.

Generally, the box press may include a frame which provides a box support and a mounting for the presser and strapping mechanism. The strapping mechanism which may or may not be employed with my improved presser mechanism is not shown. In the form of the invention illustrated, the presser mechanism comprises a framework which is mounted for vertical movement on the press frame, being spring urged to its upper inoperative position and adapted for movement by suitable adjusting means to its lower clamping position where it holds the lid of the box in position to be fastened as by nailing.

This type of press is especially useful in boxing citrus fruit, and other similar types, with which a "crown pack" is used, that is, the fruit is packed higher than the sides of the box so that the lid, when fastened, arches from end to end.

The presser mechanism usually includes a pair of spaced apart presser arms which are positioned for engagement transversely across a box lid adjacent the ends thereof and, preferably with the face of the presser arms flat against the lid. Such presser arms are mounted for adjustment on the presser framework as described more particularly hereinafter for use with various sizes of boxes.

The box press frame 10 is generally rectangular and may be formed of angles or the like which may be joined as by welding. Frame 10 is provided at the top with plate 11 to form a box support, plate 11 having upturned rear edge 12 forming a stop to engage a side of the box and position the box on the plate 11. At each end, frame 10 is provided with spaced apart guide angles 13 which provide a vertically extending track for rollers 14 journaled on presser framework 16. Framework 16, as seen more clearly in Fig. 1, is provided with vertical end angles 17 connected adjacent the top by a cross channel 18.

Framework 16 is urged to its raised inoperative position by respective sets of springs 21 (Figs. 1 and 2) secured at their upper ends to frame 10 and at their lower ends to respective brackets 22 on respective end angles 17 of the framework. To provide for adjustment of framework 16, U-shaped foot pedal 26 has its ends pivoted at 27 on diagonal frame members 28 of frame 10 and extends downwardly and forwardly of the machine and centrally thereof has pedal extension 29 for operation by the foot of an operator. Adjacent its ends, pedal 26 has respective links 31 pivoted thereto and extending upwardly through respective apertured arms 32 on framework 16. The adjusting nuts shown on the upper ends of links 31 provide means for adjusting the amount of movement of presser framework 16 caused by movement of pedal 26.

To maintain the adjusted position of pedal 26 and framework 16, arcuate latching sector 33 may have its upper end secured by suitable brackets on frame 10 and adjacent its lower end is provided with rack teeth 34 for cooperation with latch 36 adjustably mounted by set screw 37 on latch member 38 pivoted at 39 on pedal 26. Spring 41 tends to urge latch 36 into engagement with teeth 34.

From the above description it is seen that

presser framework 16 can be lowered from its upper inoperative position to the position shown in full lines in Figs. 1 and 2 by depression of operating pedal 26, such position being maintained 5 by the engagement of latch 36 with teeth 34. As stated above, this movement serves to move the presser arms into clamping engagement with the lid of a box to press the fruit into a box and hold the lid in position to be fastened. The presser 10 arms are mounted for vertical adjustment with respect to the presser framework to enable easy adaptation of the box press for use with boxes of varying sizes. Preferably, the presser arms are made in the form of attachments so that if 15 desired they can be applied to box presses already in use.

The presser arm assemblies are similar, being symmetrical for use with the respective ends of a box, for this reason only one of such presser 20 arm assemblies will be described in detail.

In the form of the invention illustrated, each presser arm assembly includes a bracket 51 (Figs. 1 and 2) having L-shaped boss 52 at its lower end for engagement with an end angle 17 of presser 25 frame 16. Boss 52 and angle 17 are provided with aligned apertures to receive fastening bolts 53. As seen more clearly in Figs. 3 and 4, each bracket 51 is provided with plate portion 56 which is especially formed to cooperate in the adjustment of the presser arm, per se.

To provide a mounting for the presser arm, plate portion 56 has apertured boss 57 to receive a reduced end of fastening stud 58 which is secured thereon by nut 59 threaded on such reduced end. Crank 61 has apertured boss 62 pivoted on an enlarged portion of stud 58 and held thereon by head 63 of stud 58. At its free end, crank 61 is provided with apertured boss 64 which pivotally receives shaft extension 66 of presser 40 arm 67, which is located with respect to boss 64 by flange 68 thereof and arm 69 pinned on extension 66 at 71. As seen in Fig. 3, presser arm 67 is provided with flat bottom face 72 to engage the lid of the box as illustrated in Fig. 1.

45 To provide for vertical adjustment of the presser arm with respect to its supporting bracket, and to control the angle of the face of the presser arm, the bracket is provided with a plurality of spaced apart fastening stations in the 50 form of apertures 76 which are adapted to receive locking pin 77 removably carried in arms 69 and held in position by latch plate 78 (Figs. 3 and 6) secured on arm 69 by screw 79. Latch plate 78 extends into a transverse slot 80 of the 55 locking pin to limit the endwise movement thereof. The locking pin is spring urged into engagement with a fastening station and can be latched in disengaged position. As illustrated in Fig. 6, the locking pin is provided with a longitudinal 60 recess 81 to receive spring 82 which is compressed between the end of the recess and latch plate 78. The parts are shown in normal position with the locking pin seated in an aperture 76. By moving the pin out of the aperture the spring is compressed and latching slot 83 at one side of slot 80 is aligned with latch plate 78 and can be engaged therewith by a slight rotation of the locking pin in either direction to latch the pin in inoperative position.

70 Preferably, an aperture or fastening station 76 is provided for each size of box to be handled. In the illustrated embodiment, four apertures 76 are provided for use with boxes of 1 1/2 bushel, 1 bushel, 1/2 bushel and tangerine size. Fig. 5 illustrates schematically the various adjusted po-

sitions of a presser arm, the full line position being the same as shown in Figs. 1 through 4 for a 1 and 1/2 bushel capacity box, the face of the presser arm being in an angled position to engage the end of an arched box lid. The small 5 dash line position represents the presser arm as located for a 1 bushel box, while the large dash line shows the arm as located for a 1/2 bushel box, and the chain lines as located for a tangerine size box. It is to be noted the angle of the presser 10 arm face is controlled by the location of the various holes 76 to insure flat engagement of such face with a box lid, while the lid is nailed, strapped, or otherwise fastened on the box.

It is seen, therefore, that the presser arms can 15 be readily adjusted vertically to correspond to the size box coming through the packing line, so that no unnecessary time need be lost in making the adjustment, and so that only one size box press need be provided for all sizes of boxes. It 20 is also to be noted that because of the unitary construction of the presser arm assembly, such assemblies can be mounted readily on box presses already in use, thereby increasing their efficiency and reducing the amount of equipment required 25 in a packing plant or the like.

While we have shown and described a preferred embodiment of the invention, it is to be understood that the form thereof is subject to variation and modification, and that the invention should be limited only by the scope of the appended claims.

We claim:

1. In a box press, a box support, and means for clamping a box on said support including a 35 bracket movable with respect to said support, a crank pivoted at one end on said bracket, a presser arm carried by said crank adjacent its free end, and adjustable connecting means between said bracket and said crank including a 40 plurality of fastening stations on said bracket and a fastening element adjacent the free end of said crank for selective engagement with said fastening stations, whereby to vary the vertical position of said presser arm relative to said 45 bracket by pivotal movement of said crank.

2. An attachment for a box press or the like having a box support and presser means movable to clamp a box on said support, comprising a bracket for mounting on said presser means 50 and having a plurality of vertically spaced apertures, a crank pivotally mounted on said bracket, a presser arm rotatably mounted in said crank and having an extension at one side thereof, and a locking pin carried by said extension and engageable with any selected aperture, whereby to change the vertical position of said presser arm relative to said bracket.

3. An attachment for a box press or the like having a box support and presser means movable to clamp a box on said support, comprising a bracket for mounting on said presser means and having a plurality of vertically spaced apertures, a crank pivotally mounted at one end on said bracket, a presser arm rotatably mounted 65 on said crank at its other end, a releasable locking pin carried by said arm and engageable with any selected aperture, to adjust the vertical position of said presser arm relative to said bracket and means for latching said locking pin in inoperative position.

4. In a box press, a box support, a presser frame mounted for vertical movement relative to said support, a crank having one end pivotally connected to said frame and having its other 75

end adjustably connected thereto, a presser arm carried by said other crank end whereby pivotal adjusting movement of said crank provides for vertical adjustment of said presser arm relative 5 to said frame, a fastening element associated with said crank, and a plurality of means on said frame engageable by said fastening element for positioning said crank and presser arm at any of a plurality of vertical positions relative to said 10 frame.

5. In a box press, a box support, a presser frame mounted for vertical movement relative to said support, a crank having one end pivotally connected to said frame, a presser arm mounted 15 at the other end of said crank, a plurality of fastening stations on said frame along the path of movement of said other crank end, and a fastening element on said crank for selective engagement with said fastening stations.

6. An attachment for a box press or the like having a box support for presser means movable to clamp a box on said support, including a bracket for mounting on said presser means, a crank pivoted at one end on said bracket for vertical swinging movement thereon, a presser arm rotatably mounted in the free end of said crank, said arm having a face for engaging a box lid, and means for holding said crank against pivotal movement at any of a plurality of vertical positions and for maintaining the lid engaging face 30 of said presser arm at an angle to insure flat engagement with a box lid.

7. An attachment for a box press or the like having a box support and presser means movable to clamp a box on said support, including a bracket for mounting on said presser means, a crank pivotally mounted on said bracket for vertical swinging movement thereon, a presser arm rotatably mounted in said crank at its free end and having a box lid engaging face, said presser arm having an extension at one side of said 35 crank, a fastening element associated with said extension, and a plurality of fastening stations on said bracket engageable by said fastening

means whereby said crank and presser arm may be held at a plurality of positions with respect to the vertical and whereby the lid engaging face of said presser arm is maintained at a predetermined angle in each of the positions. 5

8. In a box press, a box support, and means for clamping a box on said support including a presser arm having a box lid engaging face, said presser arm being adjustable vertically and also being rotatable to vary the angularity of its lid 10 engaging face, and a single means for simultaneously adjusting the vertical position of said arm and the angularity of the lid engaging face thereof for cooperation with boxes of different sizes and with lids having different degrees of 15 arch.

9. In a box press, a box support, and means for clamping a box on said support including a presser arm having a box lid engaging flat face, said presser arm being adjustable vertically and also being rotatable to vary the angularity of its lid engaging face, and means for adjusting said arm vertically with respect to said support for cooperation with boxes of different sizes, operation of said means acting to effect angular 20 adjustment of said lid engaging face for insuring flat engagement with lids having different degrees of arch. 25

10. In a box press, a box support, means for pressing a lid upon a box resting on said support and including a pair of lid pressing arms having flat lid engaging faces, means for supporting said presser arms above said box support, means for providing relative movement of said presser arm support and said box support toward and away 30 from one another, and means for adjusting said presser arms vertically with respect to their supporting means, said presser arms being associated with said adjusting means in a manner to cause angular adjustment of said lid engaging 35 faces upon actuation of said adjusting means. 40
